INVENTOR

Carl Schmid

UNITED STATES PATENT OFFICE

CARL SCHMID, OF GENEVA, SWITZERLAND

PENCIL HOLDER

Application filed May 26, 1930, Serial No. 455,929, and in Switzerland May 25, 1929.

I have filed applications in Switzerland May 25, 1929, Ser. No. 138,622, and in Germany June 21, 1929.

The attached drawings show various embodiments of the subject of the invention.

Fig. 1 shows the exterior of the first form. Fig. 2 shows on a larger scale the longitudinal section of the above.

Figs. 3, 4 and 5 give on a larger scale the longitudinal and cross sections of the clamping piece.

Figs. 6 and 7 show on a large scale the longitudinal and cross sections of a second form.

15 The lead *a* is fed into the tube *p* which is fitted with a clamping piece *c* in the point of the holder; as can be seen in Figs. 4 and 5 this clamp is provided with slots *d*. The clamp *c* which has a conical seating surface 20 the sectional cone of which is thickened towards the lead point is placed in a conical seating of the holder *h* corresponding to the conical surface of the clamping piece. The holder *h* is securely fastened to the holder 25 tube *i*. The casing *p* has a guide piece *k* and an extending tube *l* which is also arranged to act as a holder for spare leads and is closed by a cap *m*. Between the holder *h* and the guide piece *k* a spring *n* has been let in which draws 30 the clamp into the holder and thereby secures the lead in the roughened bore of the clamping tube. As a result of the friction between the lead and clamp due to the roughening of the bore of the clamping tube, pressure on the 35 lead point drives the clamp further into the holder, and thus, as the conical surface of the clamping tube is thickened sectionally towards the lead point the lead is jammed and held immovable, i. e. the position of the lead 40 in relation to the holder becomes fixed. If it is required to push the lead out or in the cap *m* must be pressed, and thus the clamp is forced out of the point of the holder, opens and releases the lead.

45 The roughening of the tube of the clamping piece (Fig. 3) may consist, for instance, of a thread, and to prevent the twisting of the lead, the front part of the thread *f* is cut right handed and the back part *g* is given a 50 left handed thread.

The spare leads *o* in the extension tube *l* (Fig. 2), on the lead *a* becoming shortened, are fed automatically into the tube *p*, when the holder is held vertically, and the complete supply of spare leads can be used in 55 this manner without any further operation being necessary. This is due to the fact that the guide piece *k* has a conical milled edge set against the cap and the spare leads lie on this conical surface. When the holder is held 60 in a vertical position the spare leads slide by gravity off the conical surface into the orifice of the guide piece *k* and thus into the casing *p*. To prevent two spare leads sliding into the aperture together and jamming, 65 the guide piece *k* is provided with an edge for about three-quarters of the circumference of the aperture which prevents more than one spare lead from falling into the casing *p* at a 70 time.

A modification (Figs. 6 and 7) is intended to permit of leads of different hardness or colours, as required, being fed from the spare lead holder into the casing *p*. This is effected by subdividing the lead holder *s*. The 75 leads are fed into the casing by turning the cap *u* with the holder in a vertical position. A guide *r* fixed to the cap *u* prevents the leads from falling from one partition in the holder 80 into the aperture of the casing *p*.

A pencil sharpener *q* can be built into the cap for the purpose of sharpening the lead (Fig. 2). The cap is removable.

I claim:

1. In a mechanical pencil, the combination 85 of a tubular pencil body, a slidable guide tube for the lead within the pencil body, resilient clamping jaws at the outer end of the guide tube and having a roughened inner surface 90 in contact with the lead, said clamping jaws having a conical outer surface increasing in diameter towards the lead point and extending over a part of that length of the jaws of which the inner surface is roughened, the 95 end of the pencil body having a conical inner surface providing a seat for the conical outer surface of said clamping jaws, and a spring inserted between the pencil body and the guide tube for normally urging the guide 100

- tube inwardly relative to the pencil body, whereby said conical inner and outer surfaces coact to evenly apply the entire length of the roughened surface of the clamping jaws against the lead.
- 5 2. In a mechanical pencil, the combination of a tubular pencil body, a slidable guide tube for the lead within the pencil body, resilient clamping jaws at the outer end of the guide tube and having their inner surface partly provided with a right hand helicoidal groove and partly with a left hand helicoidal groove, said clamping jaws having an outer conical surface extending over a part of that length of the jaws of which the inner surface is grooved, the end of the pencil body having a conical inner surface providing a seat for said conical outer surface of the clamping jaws, and a spring inserted between the pencil body and the guide tube for normally urging the guide tube inwardly relative to the pencil body.
- 10 3. In a mechanical pencil, the combination of a tubular pencil body forming a lead magazine, a guide tube for the lead slidable within the pencil body, resilient clamping jaws at the outer end of the guide tube and having a roughened inner surface in contact with the lead in the tube, said clamping jaws having a conical outer surface extending over a part of that length of the jaws of which the inner surface is roughened, the end of the pencil body being provided with a conical inner surface coacting with the conical outer sur-
- 15 face of the clamping jaws, a spring inserted between the pencil body and the guide tube for normally urging the guide tube inwards relative to the pencil body, a guide member surrounding the upper end of the guide tube and being provided with a conically shaped end face supporting the leads in the lead magazine, and means on said end face providing an entrance for one lead at the time only into the guide tube.
- 20 45 In testimony whereof, I have affixed my signature.

CARL SCHMID.
